FRANK A. YOUNG, OF MERIDEN, CONNECTICUT, ASSIGNOR TO THE TRUMBULL ELECTRIC MANUFACTURING COMPANY, OF PLAINVILLE, CONNECTICUT, A CORPORATION OF CONNECTICUT

REVERSING SWITCH

Application filed August 23, 1930. Serial No. 477,235.

My invention relates, in a general way, to the class of electrical switches commonly known as double-throw switches, such switches being generally used for changing the line circuit from one source of supply to another by moving one set of load connected movable contacts or blades from engagement with one set of line connected stationary contacts to another set.

10 While my invention possesses the general appearance and some of the characteristics of such double-throw switches, I have provided additional movable contacts and correlated mechanism so that the movement of the contacts from one running position to another will reverse the direction of the circuit which flows from the switch to the motor or other device to be controlled or operated by the switch.

20 The principal object of my invention is to provide a very compact and efficient switch construction for reversing the direction of flow of the circuit leading from the load side terminals of the switch.

25 Another object is to provide a reversing switch having the movable blades carried by an insulating rotor which rotor is pivotally mounted between the line and load side stationary contacts.

30 Another object is to provide a reversing switch having the major portion of the respective blades and the necessary cross-connections for the blades enclosed between sections of an insulating rotor and in which the 35 rotor sections and the blade members may be secured together as a unit.

Another object is to provide a reversing switch having pivotally mounted movable blades arranged for a double-break engagement with the respective stationary contacts.

Another object is to provide a reversing switch having means for releasably latching the movable blades in the intermediate or "off" position.

45 Another object is to provide an enclosed reversing switch having an external operating handle and interlocking means for preventing the opening of the cover when the switch is in either of its circuit closing positions.

Another object is to provide a reversing switch having an insulating base on which the stationary and movable contacts may be mounted to form a separable unit which may be readily secured in operable position in 55 the enclosing box.

Another object is to provide an enclosed reversing switch having a box, a cover for the box and a detachable saddle member and on which saddle member the entire switch 60 together with its operating, interlocking and latching mechanism may be mounted to form a unit which may be readily secured in position in the box or removed therefrom without disturbing any of the switch parts.

Another object is to provide a three-wire reversing switch having its contacts and parts so arranged that it may be used as a double-pole reversing switch without changing any of the parts or their co-relation.

In the embodiment of the invention as herein shown and described, pairs of stationary contacts are supported by an insulating base. Between the oppositely disposed stationary contacts, is arranged an oscillating cylinder which carries the movable switch members. The central switch member is in the form of a four-armed cross with the arms at right angles to each other, so that when the switch is closed in either direction from a central position a direct circuit is established from the line terminal to the opposite load terminal. The end switch members are divided and one part at one end of the switch carrier is connected to the oppositely disposed part at the other end of the carrier.

The corresponding switch part at the latter end is cross connected to the oppositely disposed part at the first end of the carrier, so that reversal of flow of direction of the current is effected by simply turning the switch operating handle in one direction or the other from the circuit "off" position. Other switch blades of the end units extend at right angles to the divided blades and are insulated from them. The movable switch member is made up of a number of insulating sections which carry the movable arms and are held together by a central tie rod.

Fig. 1 is a front view of a switch embody-

ing my invention, with a part of the protecting part broken away and the cover of the box broken.

Fig. 2 is a transverse sectional view, the parts being in the closed circuit position.

Figs. 3, 4, and 5 are perspective views showing parts of the movable switch member.

Fig. 6 is a longitudinal sectional view and side elevation showing the switch actuating mechanism.

Fig. 7 is a sectional view of the switch proper showing the members and the end units of the switch in one of the closed circuit positions.

Fig. 8 is a similar sectional view showing the switch member for the central unit.

The insulating base 10 carries all conducting parts of the switch. The load terminals 11, 12 and 13 are arranged along one edge of the base and the line terminals 14, 15 and 16 along the opposite edge of the base. A pair of stationary contact jaws such as 17 and 18, 19 and 20 are connected to each of the circuit terminals.

The rotatable switch member has an insulating body made up of the cylindrical portions 21, 22, 23, 24, 25 and 26 held together by the end plates 27 and 28 and a tie rod 29, which is supported on brackets 30-31. These brackets are also connected at the top by an insulating plate 32 which covers the conducting parts and provides arc-confining channels 33 for the movable switch members.

Insulating plates 34 and 35 are interposed between the brackets 30-31 and the adjacent switch units. These plates may be formed of insulating fibre and are supported in grooves in the base and cover plates. Other insulating plates (not shown) may be supported in grooves such as 36 between the adjacent switch units if desired.

The central switch member has arms 40-41, 42-43 supported in recesses between the insulating sections 23 and 24. Switch member 44 is mounted between the members 22 and 23 and preferably in a groove 45. At the opposite end of the switch carrier, a switch member 46 is mounted between the parts 24 and 25 preferably in a groove 47. The ends of the members 44 and 46 are offset from their central portions so as to bring them into approximately the central planes of the discs 22 and 25 and in line with the passages between the jaws of the adjacent stationary contacts.

Switch blades 50 and 51 have feet positioned in grooves 52 and 53 between the insulating members 21 and 22. These members 50 and 51 may have lugs 54 and 55 adapted to project into grooves such as 56 in the insulating part 21 to assist in anchoring them.

Blades 60 and 61 at the opposite end of the switch carrier are likewise secured between the insulating discs 25 and 26. The mem-

bers 50 and 61 are electrically connected by a rod 62. The switch blades 51 and 60 are connected by a conducting rod 63. These rods pass through openings 64 and 65 in the central switch member but are insulated from it. Pins such as 66 are also preferably provided for anchoring the various switch members to the conducting cylinder. These pins may project through perforations such as 67 into recesses such as 68.

It will be understood that the rods 62 and 63 extend through the switch blades 50, 51 and 60 and 61 as well as the intervening insulating members 22, 23, 24, and 25 so that they may assist in securing the parts together independently of the central tie rod 29, which serves as a main shaft or bearing for the switch carrier.

In the form shown the contact mechanism and the supporting base 10 are mounted on a plate 70 which has a tongue 71 interlocked in the corner of the box 72. This bottom plate 70 has a side flange 73 which serves as a closure for one side of the box and which carries the handle 74 and the switch actuating mechanism 75 of suitable type.

The hub of the handle has an interior fork arm 76 engaging a pin 77 which is carried by the end plate 28 of the oscillating switch carrier. An arm 80 is hinged at 81 to the side plate 73 and is pressed by a spring 82 toward the cam 83. This spring 82 and arm 80 thus coact with one or more flattened surfaces 84 and tend to hold the handle and movable switch parts in the open circuit position and to resist movement of the operating handle toward the closed circuit position. Normally in the open circuit position the handle 74 projects at right angles to the main plane of the switch. The flanges 85 and 86 serve as limiting stops to the movement of the handle and for the attachment of the padlocks or sealing wire for locking the handle in the closed circuit position.

When the handle is raised the blades 44 and 46 are in engagement with the upper and lower contact jaws respectively and the current passes through the switch in one direction. When the switch handle is moved to its lowest position the contact blades 51-50 and 61-60 engage the corresponding stationary jaws and the circuit is reversed because, for instance, the blade 50 which is now connected to circuit terminal 14 is electrically connected through the rod 62 to the blade 61 which is connected to the circuit terminal 13 and the blade 51 which is connected to the terminal 11 (through the stationary contact blades not shown) is connected through rod 63 to blade 60 and thence to terminal 16.

It will thus be seen that I have provided a three pole double break reversing switch which is very compact and yet fully protected by insulation. All of the parts are so

constructed and mounted that they can be readily inserted as a unit into an installed box and readily detached for repair and replacement when necessary. Obviously the same construction may be used for a double pole reversing switch by merely connecting the line wires to terminals 14 and 16 and the load side wires to terminals 11 and 13 and leaving the central or neutral switch members unused.

10 Obviously the combination of elements shown and described may be electrically connected or wired so as to produce different directions of the path of the electrical circuits.

15 Although 14, 15 and 16 have been described as line terminals, it is readily apparent that the line wires may be secured to terminals 11, 12 and 13, in which case 14, 15 and 16 become the load side terminals.

20 I claim:

1. A reversing switch including at least two pairs of stationary contacts, a switch member rotatable between said contacts and comprising a number of insulating members, 25 two pairs of divided conducting blades each pair being secured between two of said insulating members, two double ended blades each secured between two of said insulating members, and having contact portions in the same 30 plane as the contact ends of the divided blades of each pair and rods connecting each of the divided blades with the oppositely disposed member of the other pair of divided blades.

35 2. A switch including stationary contacts and an oscillating carrier having three switch units mounted thereon, one unit comprising a conductor having four connected blades, each of the other units comprising a double 40 ended blade and two half blades with their contact ends in the same plane as the contact ends of the associated double ended blade, but at substantially right angles thereto and conducting rods connecting the half blades of 45 one unit with the opposite half blades of the other unit.

3. A switch comprising stationary contacts, an oscillatable insulating carrier, a series of switch blades carried thereby for engagement 50 with the contacts, a handle connected for oscillating the carrier, a cam member carried by the handle and having a flattened portion and a spring pressed lever coacting with said flattened portion for holding the carrier 55 yieldingly in the "off" position.

4. A reversing switch including three pairs of stationary contacts, a switch member rotatable between said contacts and comprising a number of insulating members, a pair of 60 divided conducting blades secured between some of said members, double ended blades secured between some of said members, and having contact portions in the same planes as the contact ends of the corresponding divided 65 blades, rods connecting halves of the divided

blades with the opposite halves of the other divided blades and a four bladed switch member held between some of the insulating members and coacting with the contacts of another pair of stationary contacts.

5. A switch including stationary contacts and an oscillating carrier having three switch units mounted thereon, one unit comprising a conductor having four connected blades, each of the other units comprising a double ended blade and two half blades with their contact making ends in the same plane as the contact making ends of the associated double ended blade but at substantially right angles thereto, and conducting rods connecting the half blades of one unit with the opposite half blades of the other unit and means for yieldingly holding the carrier in the open circuit position.

6. A switch comprising stationary contacts, an oscillatable insulating carrier, a switch unit carried thereby and having four spaced blades projecting at approximately ninety degrees apart for engagement with some of the contacts, and two other units carried by the carrier and each unit having two blades cross-connected within the carrier, a handle connected for oscillating the carrier, a cam member carried by the handle and having a flattened portion and a spring pressed lever coacting with said flattened portion for holding the carrier yieldingly in the "off" position.

7. A switch comprising stationary contacts, an oscillatable insulating carrier, a switch unit carried thereby and having four projecting blades spaced at approximately ninety degrees around the carrier for engagement with some of the contacts and two other units carried by the carrier and each having two blades cross-connected within the carrier.

8. A reversing switch including pairs of stationary contacts, a switch member rotatable between said contacts and comprising a number of insulating members, a four armed blade secured between two of said insulating members, a pair of divided conducting blades secured between two of said insulating members, double ended blades secured between two of said members, and having contact portions in substantially the same plane as the contact ends of the divided blades, and rods connecting halves of the divided blades with the opposite halves of the other divided blades.

9. A switch including stationary contacts and an oscillating carrier consisting of insulating sections and having three switch units mounted thereon, one unit comprising a blade having four connected contact portions, each of the other units comprising a double ended blade and two half blades with their contact ends in the same plane as the contact ends of the associated double ended blade but at substantially right angles thereto, conducting

- rods connecting the half blades of one unit with the opposite half blades of the other unit and a central tie rod connecting all of the insulating sections.
- 5 10. A switch comprising stationary contacts, an oscillatable insulating carrier, a switch unit carried thereby and having projecting blades for engagement with the contacts, other switch units having cross connected divided blades, a handle connected for oscillating the carrier, a cam member carried by the handle and having a flattened portion, a spring pressed lever coacting with the flattened portion of said cam member 15 for holding the carrier yieldingly in the "off" position.
11. A reversing switch including at least two pairs of stationary contacts, a switch member rotatable between said contacts and comprising a number of insulating members, positioning pins connecting said insulating members, a pair of divided conducting blades and a double ended blade secured between two of said members, the contact end of said 25 double ended blade being in the same plane as the contact ends of the divided blades and rods connecting halves of the divided blades with the opposite halves of the other divided blades.
- 30 12. A switch including stationary contacts and an oscillating carrier having three switch units mounted thereon, one unit comprising a conductor having four integral projecting blades, each of the other units comprising a double ended blade and two half blades with their contact making ends in substantially the same plane as the contact making ends of the associated double ended blade, conducting rods connecting each of the half blade 35 members of one unit with the opposite half blade member of the other unit and means for yieldingly holding the carrier in its "off" position.
13. A reversing switch including an insulating base, pairs of stationary contacts mounted on said base, an insulating blade carrier pivotally mounted between the respective pairs of stationary contacts and two sets of switch blades, each set including a blade 45 having a contact portion at each of its opposite ends and a pair of separated blades, each blade having a contact portion at one of its ends, all of the members of each set of blades being mounted in co-related position on said 50 carrier with all of the said contact portions projecting in the same plane and each member of each of one of said pairs of blades being electrically connected with an oppositely disposed blade of the other said pair 55 of blades.
14. A reversing switch including an insulating base, pairs of stationary contacts mounted on said base, an insulating blade carrier mounted between the respective pairs 60 of stationary contacts, a switch blade mount- ed on said carrier and having four projecting contact portions spaced at approximately ninety degrees with respect to each other and two sets of switch blade members mounted on said carrier, each set including a blade having a contact portion at each of its opposite ends and a pair of spaced blades each blade having a contact portion at one of its ends, all of the members of each set of blades being mounted in corelated position on said carrier 70 with all of said contact portions in the same plane and each blade of each of said pairs of blades being electrically connected with an oppositely projecting blade of the other said pair of blades.
- 75 15. A reversing switch including an insulating base, pairs of spaced stationary contacts mounted on said base, a blade carrier mounted between the respective pairs of stationary contacts and composed of sections of insulating material together with means for securing said sections together as a unit, a switch blade mounted between two sections of said carrier and having four projecting contact portions and two sets of corelated 80 blades, each set including a blade having a projecting contact portion at each of its opposite ends and a co-related pair of blades each having a single projecting contact portion, all of the members of each of said sets of blades being mounted between other sections of said carrier with all of the projecting contact portions in the same plane and each member of each of said pairs of blades being 85 electrically connected with an oppositely projecting member of the other pair.
- 90 16. A reversing switch including at least two pairs of stationary contacts, a switch member rotatable between said contacts and comprising a number of insulating members, a pair of divided conducting blades secured between some of said members, double ended blades secured between some of said members, one being in the same plane as the ends of the divided blades of each pair and rods connecting halves of the divided blades with the 95 opposite halves of the other divided blades.
- 105 17. A switch comprising stationary contacts, an oscillatable insulating carrier, a switch unit carried thereby and having four projecting blades spaced at approximately 110 ninety degrees around the carrier for coacting with some of the contacts, a handle connected for oscillating the carrier, a cam member carried by the handle and having a flattened portion and a spring pressed lever coacting with said flattened portion for holding the carrier yieldingly in the "off" position.
- 120 18. A reversing switch including pairs of stationary contacts, a switch member rotatable between said contacts and comprising a number of insulating members, a four armed plate secured between some of said insulating members, a pair of divided conducting blades 125

secured between some of said insulated members, double ended blades secured between some of said members, one being in substantially the same plane as the ends of the divided blades of one pair and rods connecting halves of the divided blades with the opposite halves of the other divided blades.

19. A reversing switch including at least two pairs of stationary contacts, a switch member rotatable between said contacts and comprising a number of insulating members positioning pins connecting said insulating members, a pair of divided conducting blades secured between some of said members, double ended blades secured between some of said members, one being in the same plane as the ends of the divided blades of each pair and rods connecting halves of the divided blades with the opposite halves of the other divided blades.
